UNITED STATES PATENT OFFICE.

CREASEY J. WHELLAMS AND ALFRED G. PINKHAM, OF ST. PAUL, MINNESOTA.

DESIGN FOR A SOUVENIR-SPOON.

No. 39,440.

Specification for Design.

Patented Aug. 11, 1908.

Application filed February 13, 1908. Serial No. 415,758. Term of patent 3½ years.

To all whom it may concern:

Be it known that we, CREASEY J. WHELLAMS and ALFRED G. PINKHAM, citizens of the United States, residing at St. Paul, in the county of Ramsey and State of Minnesota, have invented a new, original, and ornamental Design for a Souvenir-Spoon, of which the following is a specification, reference being had to the accompanying drawing, forming part thereof.

The figure is a plan view of the souvenir spoon showing our new design.

We claim:

The ornamental design for a souvenir spoon, as shown.

CREASEY J. WHELLAMS.
ALFRED G. PINKHAM.
